COMBINED FILLER AND DRAINER

William H. Scott, Rochester, N. Y.

Application March 13, 1944, Serial No. 526,303

8 Claims. (Cl. 103—262)

This invention relates to a combined filler and drainer.

In my Patent 1,630,543 granted May 31, 1927, there is disclosed a filling and draining device which has been widely and conveniently used to fill a wash tub from the hot and cold faucets of a sink or to drain the contents of the tub into the sink. However, certain health authorities have objected to the use of this arrangement pointing out that if, under emergency conditions, the pressure of the water supply drops while the connection exists to the cold water faucet, the drain water can be drawn into the water system with a possible pollution thereof.

The present invention has for its purpose the production of a combined filler and drainer which retains all of the convenience and advantages of the device disclosed in my patent while obviating the possibility of polluting the water supply under the conditions mentioned.

For a clear understanding of the invention, reference is made to the drawing in which:

Fig. 1 is a perspective view of the filler and drainer device of this invention related to a sink with its faucets as well as related to a tub to be filled and emptied by the device;

Fig. 2 is a front view, partly broken away, of the aspirator unit with its coupling element, both as used in the device;

Fig. 3 is a vertical section taken through the parts of Fig. 2; and

Fig. 4 is a vertical sectional view of an aspirator unit provided with a modified coupling element.

The combined filler and drainer of this invention includes an aspirator unit 5 provided with a coupling element 6 arranged to be connected preferably to the cold water faucet 7. The unit 5 is likewise provided with connection nipples 8, and 9. The nipple 8 has attached thereto, a piece of hose 10 of a convenient length for connection, by means of a coupling element 11, to the hot water faucet 12. The coupling element 11 is similar in construction to that of the coupling element 6a (Fig. 4). The hose 10 preferably is long enough to reach the bottom of the sink 13 into which the faucets normally discharge when the filler and drainer is disconnected. The nipple 9 likewise has connected thereto, a piece of hose 15 of a length sufficient to reach to the very bottom of a tub 16 located near the sink.

With this arrangement, when the hose 10 is connected to the faucet 12, as shown in dotted lines in Fig. 1, and when the free end of the hose 15 is placed in a tub 16, the faucets 7 and 12 can be manipulated to fill the tub with water at the

desired temperature. However, when it is desired to drain the tub, the free end of the hose 15 is placed on the bottom of the tub. Thereafter, the hose 10 is disconnected from the hot water faucet 12, which is now closed, and the free end of this hose is placed in the sink 13, as illustrated. The cold water faucet 7 is then opened so that cold water flows through the aspirator unit 5 and through the hose 10 into the sink. As this cold water thus flows through the unit, it also withdraws and carries with it water drained through the hose 15 from the tub 16 to be emptied.

The improved construction of the present invention preserves the convenience and utility of the device disclosed in my mentioned patent but eliminates even the remote possibility of pollution of the water supply under the conditions mentioned above. The present device includes a novel aspirator unit 5 shown with one type of coupling element in Figs. 2 and 3 and shown with another type of coupling element in Fig. 4. In its preferred form, the aspirator unit comprises an elongated body provided at its lower end, as shown, with the previously mentioned connection nipple 8, and provided at its side with the mentioned connection nipple 9. The upper end of the body has a reduced portion 19, into which there is forcibly telescoped a nozzle or jet 20 opening into the enlarged chamber 21 within the body, and directed toward the nipple 9. The side wall of the jet 20 is provided with spaced indentations 22 which normally support a glass ball 23 in a position where water can flow past it. This ball in its abnormal position (see dotted line position Fig. 3) cooperates with a trap 24. This trap which is provided with at least one ball seat 25, is in the form of a sleeve having a forced fit with the interior of the jet. For convenience in assembly, both ends of the trap are provided with a ball seat so that there is no possibility of incorrect assembling. The mentioned upper end of the reduced portion 19 is provided with a coupling element. This coupling element, in the modification illustrated in Figs. 2 and 3, is in the form of a rubber head 27 adapted to fit over the unthreaded end of a faucet being retained thereon by a divided clamping ring 28. In the preferred construction, the head 27 is molded from rubber having embedded therein the flange 29 on the upper end of the jet 20. The part of the head adjacent the body portion 19 is encased in a reinforcing metal ferrule 30 having an in-turned flange 31.

It will be noted that the several parts of the

unit are forcibly fitted together for quick and easy assembling. Thus, the ferrule 30 is easily forced on the head which has molded therein, the flange 29 of the jet. These parts, when put together in this manner, can be assembled on the aspirator unit by forcibly fitting the jet into the reduced portion 19 of the body until the various parts occupy the position shown in Fig. 3. The trap 24 can be forcibly fitted in the jet 20 after the glass ball 23 has been placed therein. The forced fits between the several parts avoids leaks and affords economy in manufacture.

The modified form of the invention shown in Fig. 4, differs from that already described in that a coupling element for use with a screw type faucet is employed. In this modified device, the coupling element 6a is internally threaded for engagement with the threaded outlet of a faucet. This element is provided with a flange 33 which engages the flange 29 of the jet 20, a rubber washer 34 fits within the coupling element against the flange 29.

Under normal conditions the device functions as pointed out above. However, when the pressure in the water supply drops to a value where the direction of flow through the faucet would be reversed, the ball valve 23 engages the seat 25 on the trap 24, as shown in the dotted position in Fig. 3. The ball valve and trap thus constitute a vacuum break which eliminates the possibility of drain water entering the water system through the device.

What I claim is:

1. A receptacle filling and draining device comprising a T-shaped body having openings in its three ends, two of said openings being substantially in alinement, a coupling adapted to connect a first one of said last-mentioned openings to a water supply, a jet closely fitting in said mentioned opening and directed toward the second alined opening, a sleeve closely fitting in said jet, said sleeve being provided with a valve seat, a valve element cooperating with said valve seat, and a piece of hose communicating with the remaining opening in said body.

2. A receptacle filling and draining device comprising a T-shaped body having openings in its three ends, two of said openings being substantially in alinement, a coupling adapted to connect a first one of said last-mentioned openings to a water supply, a jet closely fitting in said mentioned opening and directed toward the second alined opening, a sleeve closely fitting in said jet, said sleeve being provided with a valve seat, a valve element cooperating with said valve seat, a hose communicating with said second alined opening and terminating in a coupling adapted to be connected to a water supply, and a piece of hose communicating with the remaining opening in said body.

3. A receptacle filling device comprising a hollow unit having three openings therein, a coupling element adapted to connect a faucet to one opening in the unit, said coupling element comprising a hollow head of flexible material adapted to embrace said faucet and an adjustable clamp encircling said head to tighten the engagement of the head with the faucet, a hose communicating with a second opening in said unit, said hose terminating in a second coupling element adapted to be connected to a second faucet, a second piece of hose communicating with said third opening and being of a length sufficient to reach into a receptacle to be filled, and a check valve within said device above the level

of the liquid in the receptacle and effective to interrupt communication from said second hose to said first coupling element in the event that the direction of flow through said first coupling element tends to be reversed.

4. An ejector type receptacle filling and draining device comprising a T-shaped body having an enlarged chamber therein and provided with three reduced ends, each provided with an opening which communicates with said chamber, two of said openings being substantially in alinement, a coupling adapted to connect a first one of said last-mentioned openings to a water supply, a jet forcibly telescoped in said first opening to discharge into said chamber in the direction of the second alined opening, said jet having spaced inwardly directed projections in the side wall thereof intermediate its ends, a sleeve closely fitting in said jet, said sleeve being provided with a valve seat, a ball valve element normally resting on said projections and arranged to engage said seat, a hose communicating with said second alined opening and terminating in a coupling adapted to be connected to a water supply, and a piece of hose communicating with the remaining opening in said body, said ball valve element and said seat cooperating to prevent a reverse flow through said jet and through said second piece of hose in the event that a siphon effect is created while the ejector is in operation.

5. A receptacle filling device comprising a hollow body having three openings therein, a coupling element adapted to connect a faucet to a first opening in the body, a hose communicating with a secnd opening in said body, said hose terminating in a second coupling element adapted to be connected to a second faucet, a second piece of hose communicating with said third opening and being of a length sufficient to reach into a receptacle to be filled, and a check valve unit between said coupling and said second opening to permit flow through said first opening into said body, said valve unit being responsive to conditions tending to cause flow in the reverse direction through said first opening for interrupting communication between said body and said coupling.

6. A receptacle filling and draining device comprising a hollow unit having three openings therein, a coupling element adapted to connect a faucet to a first opening in the unit, a jet communicating with said first opening and being directed into the unit, a hose communicating with a second opening in said unit, said hose terminating in a second coupling element adapted to be connected to a second faucet, a second piece of hose communicating with said third opening and being of a length sufficient to reach into a receptacle to be filled, and a valve interposed between said jet and said first opening, said valve comprising a valve seat and a valve member movable to an open position as well as to a closed position in engagement with said seat, and a support associated with said valve in spaced relation to said seat for supporting said valve member in its open position.

7. A receptacle filling device comprising a body having a chamber therein and provided with at least two ends, each provided with an opening which communicates with said chamber, a flexible coupling adapted to connect a first one of said openings to a water supply, said coupling comprising a hollow head adapted to embrace a faucet or like outlet, an adjustable element en-

circling an intermediate portion of said head to cause said head to grip said faucet, a ferrule encircling and reinforcing a portion of said head adjacent its junction with said body, a tube telescoped in said first opening, said tube having a part anchoring said head to said body, said tube having an internal support intermediate its ends, a sleeve closely fitting in said tube, said sleeve being provided with a valve seat, a ball valve element normally resting on said support but arranged to engage said seat, and a piece of hose communicating with the remaining opening in said body, said ball valve element and said seat cooperating to prevent a reverse flow through said tube in the event that a siphon effect is created while the device is in operation.

8. An aspirator type receptacle filling and draining device comprising a body having a chamber therein and provided with three ends, each provided with an opening which communicates with said chamber, two of said openings being substantially in alinement, a flexible coupling adapted to connect a first one of said last-mentioned openings to a water supply, said coupling

comprising a hollow head adapted to embrace a faucet or like outlet, an adjustable element encircling an intermediate portion of said head to cause said head to grip said faucet, a ferrule encircling and reinforcing a portion of said head adjacent its junction with said body, a jet forcibly telescoped in said first opening to discharge into the chamber in the direction of the second alined opening, said jet having a part anchoring said head to said body, said jet having a support therein intermediate its ends, a sleeve closely fitting in said jet, said sleeve being provided with a valve seat, a ball valve element normally resting on said support but arranged to engage said seat, 15 a hose communicating with said second opening and terminating in a coupling adapted to be connected to a water supply, and a piece of hose communicating with the remaining opening in said body, said ball valve element and said seat cooperating to prevent a reverse flow through said jet and through said second piece of hose in the event that a siphon effect is created while the device is in operation.
